UNITED STATES PATENT OFFICE.

LUIGI BELLUSCIO, OF ROCHESTER, NEW YORK.

SIDE CAR FOR MOTORCYCLES.

1,383,900.

Specification of Letters Patent.

Patented July 5, 1921.

Application filed July 31, 1920. Serial No. 400,470.

To all whom it may concern:

Be it known that I, LUIGI BELLUSCIO, a subject of the King of Italy, residing at Rochester, in the county of Monroe and State of New York, have invented new and useful Improvements in Side Cars for Motorcycles, of which the following is a specification.

The object of my present invention is the provision of a side car construction generally with a view to simulating a submarine, and embodying many points of practical advantage.

To the attainment of the foregoing the invention consists in the improvement as hereinafter described and definitely claimed.

In the accompanying drawings, hereby made a part hereof:

Figure 1 is a side elevation of my novel side car.

Fig. 2 is a plan view of the same with the cock pit closed.

Fig. 3 is a longitudinal vertical central section taken through the body of the car.

Fig. 4 is a transverse section taken in the plane indicated by the line 4—4 of Fig. 3.

Similar numerals of reference designate corresponding parts in all of the views of the drawings.

My invention resides in the body 1 of the side car, and by comparison of Figs. 1 to 4 it will be observed that the body is made to simulate a marine vessel of submarine type. This end is further attained by the employment of the combined wind shield and canopy hereinafter definitely described.

The body 1 is hollow and is provided from a point in rear of its transverse median line to its forward end with what may be properly designated a cock pit 3 inasmuch as the same is designed to receive the lower portion of the body and the limbs of a passenger. The cock pit 3 is provided with an opening 4 to enable a passenger to readily enter and leave the body 1. The said opening 4 is designed when the body is unoccupied to be tightly closed by a door 5, the function of which is to exclude the weather. The door 5 is hinged at 6 and is so relatively arranged as to form a back rest when opened as appears in Fig. 3. The body 1 is provided in the cock pit 3 with a floor board 7 on which is a raised portion 8, designed to enable a passenger disposed on the seat 9 to brace himself or herself while rid-

ing. It will also be noted in this connection that in front of the opening 4 the body 1 is provided at the inner side of its top wall with a swell or enlargement 9' against which a passenger may brace himself or herself when leaning forwardly in the opening 4. Externally the body 1 is provided with a lower step 10 and an upper step 11 spaced from the step 10, the two steps being designed to enable a passenger to gracefully enter and leave the body. At its forward end the body 1 is provided with an isolated chamber 12 in which is arranged a reflector 13 and an incandescent electric lamp 14. At the rear end of the body 1 is a similar isolated chamber 15 to receive a reflector 16 in which is disposed an incandescent lamp 17 the bulb of which is red so as to enable it to serve as a danger signal. The filaments of the lamps 14 and 17 will be electrically connected with the lighting system of the motorcycle with which my novel side car is associated. This, however, is not of the essence of my present invention and need not therefore be described in detail. Separated by walls 18 and 19 from the cock pit 3 and the chamber 15, respectively, is a gasoline tank 20 which as will be readily noted is possessed of large capacity and is therefore designed particularly to carry a reserve supply of gasoline for a long trip. In the preferred embodiment of my invention the said gasoline tank is equipped with a quantity gage 21, a normally closed filling opening 22 and a discharge conduit 23, the latter being designed to be connected in any approved manner with the explosion chamber of the internal combustion engine comprised in the motorcycle with which the said car is associated. It will also be noted that I prefer to equip the gasoline tank with a pump 24 so that the said tank may be charged with air under pressure for gasoline feed purposes.

Arranged on a circular track 25 on the top wall of the body 1 is a combined wind shield and canopy 26. The wind shield portion of the combined device 26 is of such shape in horizontal section as to describe a part of a circle, and the track 25 is correspondingly shaped. Said wind shield portion is provided with a preferably glazed opening 27, and the canopy portion of the combined device is carried at right angles to the wind shield portion so as to rest above the head of the passenger on the seat 9. In inclement

weather the combination device is arranged with the circular wind shield portion in front of the opening 4 and so that the canopy portion extends rearwardly from the 5 wind shield portion, in which position the said canopy portion may be utilized to support a water proof (not illustrated). In good weather the wind shield portion of the combination device is adapted to be positioned 10 at the outer side of the opening 4 in which position the wind shield portion will serve in a measure to protect the passenger against flying gravel and the like. At the same time the canopy portion of the 15 combination device will rest over and protect the passenger from the sun.

Having described my invention, what I claim and desire to secure by Letters Patent, is:—

20 1. A motorcycle side car body shaped to simulate a submarine and having chambers in its forward and rear end portions and also having a gasoline tank in its rear portion and a cock pit between the gasoline 25 tank and the forward chamber, said cock pit being in communication with an opening in the top of the body, a combined hinge top and back rest complementary to the said opening, and lamp holding means arranged 30 in the said forward and rear chambers of the body.

2. A motorcycle side car body shaped to simulate a submarine and having chambers in its forward and rear end portions and also 35 having a gasoline tank in its rear portion and a cock pit between the gasoline tank and the forward chamber, said cock pit being in communication with an opening in the top of the body, a combined hinged top and back 40 rest complementary to the said opening, and lamp holding means arranged in the said forward and rear chambers of the body; the said gasoline tank being equipped with a quantity gage and with means for the trans- 45 fer of gasoline from the tank to the internal

combustion engine of a motorcycle associated with the side car, and incandescent electric lamps arranged in the holders of the body and equipped with means for electrically connecting them with a source of electric energy.

3. A motorcycle side car body of hollow form having a cock pit opening in its top and also having a circular track extending in front of and at one side of the said opening, in combination with an adjustable wind shield of arcuate form in horizontal section and movable on said track to and from a position in front of the cock pit opening.

4. A motorcycle side car body of hollow form having a cock pit opening in its top and also having a circular track extending in front of and at one side of the said opening, in combination with an adjustable wind shield of arcuate form in horizontal section 65 and movable on said track to and from a position in front of the cock pit opening; the said wind shield having at its upper end a horizontal canopy portion.

5. A hollow side car body having a cock 70 pit and an opening in its top wall in communication with the cock pit and also having in rear of the cock pit a gasoline tank, and a hinged door complementary to said opening and adapted when raised to serve as a back 75 rest.

6. A hollow side car body having a cock pit and an opening in its top wall in communication with the cock pit and also having in rear of the cock pit a gasoline tank, and a 80 hinged door complementary to said opening and adapted when raised to serve as a back rest; said body being provided with an interior seat and an interior foot rest brace and also provided in front of said opening with a swell or thickened portion and being equipped exteriorly with steps to enable a passenger to readily enter and leave the body.

In testimony whereof I affix my signature.

LUIGI BELLUSCIO.
